Attorney.

UNITED STATES PATENT OFFICE.

PAUL RUDERT, OF TARENTUM, PENNSYLVANIA.

SOUND-BOX FOR SOUND-REPRODUCING MACHINES.

1,226,262.

Specification of Letters Patent.

Patented May 15, 1917.

Continuation of application Serial No. 28,020, filed May 5, 1915. This application filed January 31, 1917. Serial No. 145,624.

To all whom it may concern:

- Be it known that I, PAUL RUDERT, a citizen of the United States, and a resident of Tarentum, in the county of Allegheny and State of Pennsylvania, have invented a new and useful Improvement in Sound-Boxes for Sound-Reproducing Machines; and I do hereby declare the following to be a full, clear, and exact description thereof.
- 10 My invention pertains to sound boxes for sound reproducing machines and the like. It is the principal object of the invention to improve upon the tonal qualities of the sound reproduced by such instrument.
- 15 A sound box constructed in accordance with my invention is described, by way of example, in the following specification, and shown in the accompanying drawing, in which—
- 20 Figure 1 is a front view of a sound box having the front plate and horn receiving tube removed, thereby to disclose the intermediate diaphragm; and
- 25 Fig. 2 is a section taken longitudinally through the sound box, the front plate and horn receiving tube being shown in elevation. The section is taken as on the line 2—2 of Fig. 1.
- Referring to the drawing, the sound box
- 30 comprises a cylindrical open-ended casing 10, having an inwardly extending flange 11 at its rear end. The open rear end of the casing 10 is covered by an ornamental perforated plate 12. Upon the flange 11 are placed a pair of annular washers 13 and 14, respectively, the washer 14 bearing the vibratory diaphragm 15 which may be of any of the well known constructions. To the center of the diaphragm 15 is connected a
- 35 needle bar 16, which is connected to a suitably mounted needle socket 17. Like the diaphragm, the needle bar and needle socket may be of any of the well known constructions.
- 40 Upon the periphery of the vibratory diaphragm 15 is placed an annular washer 18, and upon this, in turn, is placed a disk 19. Upon the periphery of the disk 19 is placed an annular washer 20, the latter being of such dimensions as to extend slightly
- beyond the front end of the casing 10. The projecting edge of the washer 20 is engaged by a front plate 21 which is secured, in any suitable way, to the casing 10. This front plate 21 is apertured at its center and carries a tube 22 of the character ordinarily used for being connected to the horn extension, or swinging arm, of a gramophone or other sound reproducing machine. It will be seen that, when the front plate 21 is secured in place, it will clamp the disk 19 and diaphragm 15 firmly in position between their respective washers.
- 55 The disk 19 is made sufficiently heavy not to be capable of material vibration and is imperforate, except at points near its periphery where it is provided with a plurality of holes 23. I have found that by the provision of a disk, such as the disk 19, intermediate the vibrating diaphragm and the central sound-exit opening of a sound box, which disk is provided with openings adjacent its periphery, the tonal qualities of the sound reproduced by the device are much improved and corrected.
- 60 Having thus fully described my invention, what I claim as new and desire to secure by Letters Patent is:—
- 65 A sound box for talking machines or the like, comprising a cylindrical casing having a sound-exit opening disposed centrally of one end thereof, a diaphragm carried by said casing, means for transmitting vibrations to said diaphragm, said transmitting means being attached solely to the center of said diaphragm, a disk on the side of said diaphragm toward said opening, said disk being substantially parallel with said diaphragm and being spaced a material distance therefrom and from said end, and said disk being imperforate at and adjacent its center and being formed with apertures adjacent the periphery thereof.
- 70
- 75
- 80
- 85
- 90
- 95
- In testimony whereof, I the said PAUL RUDERT, have hereunto set my hand.

PAUL RUDERT.
